UNITED STATES PATENT OFFICE.

HOLLINGSWORTH PEARCE, OF PHILADELPHIA, PENNSYLVANIA, ASSIGNOR TO PHILADELPHIA STORAGE BATTERY COMPANY, OF PHILADELPHIA, PENNSYLVANIA, A CORPORATION OF PENNSYLVANIA.

DESIGN FOR AN ESCUTCHEON PLATE.

Application filed March 19, 1928. Serial No. 25,915. Term of patent 14 years.

To all whom it may concern:

Be it known that I, HOLLINGSWORTH PEARCE, a citizen of the United States, residing in Philadelphia, Pennsylvania, have invented a new, original, and ornamental Design for an Escutcheon Plate, of which the following is a specification, reference being had to the accompanying drawing, forming part thereof, in which:

Figure 1 is a front elevation of an es-

cutcheon plate made in accordance with my invention;

Fig. 2 is a section on the line 2—2, Fig. 1, and

Fig. 3 is a section on the line 3—3, Fig. 1.

I claim:

The ornamental design for an escutcheon plate, as shown.

HOLLINGSWORTH PEARCE.
